United States Patent Office

Des. 231,900

Patented June 25, 1974

231,900

ADJUSTABLE DOOR SUPPORT

Kenneth E. Hewson, 626 Colony Drive,
Troy, Mich. 48084

Filed July 18, 1973, Ser. No. 380,287

Term of patent 14 years

Int. Cl. D8—09

U.S. Cl. D8—233

Fig -1

Fig -2

Fig -3

Fig -4

FIG. 1 is a perspective view illustrating an adjustable door support showing my new design;

FIG. 2 is a top plan view thereof;

FIG. 3 is a side elevational view thereof and which view is identical to all other side views of the adjustable door support; and

FIG. 4 is a bottom plan view thereof.

I claim:

The ornamental design for an adjustable door support, as shown and described.
